WILLIAM B. TROST AND FRANK KLEIN, OF WATERLOO, IOWA, ASSIGNEES TO
WATERLOO-PLAYFORD SILO COMPANY, OF WATERLOO, IOWA, A CORPORATION OF IOWA.

SECTIONAL SILO-LADDER.

1,308,881.

Specification of Letters Patent.

Patented July 8, 1919.

Application filed April 20, 1918. Serial No. 229,738.

To all whom it may concern:

Be it known that we, WILLIAM B. TROST and FRANK KLEIN, citizens of the United States of America, and residents of Waterloo, Blackhawk county, Iowa, have invented certain new and useful Improvements in Sectional Silo-Ladders, of which the following is a specification.

Our invention relates to improvements in sectional ladders for silos, and the object of our improvement is to supply for use on silos a sectional ladder, whose sections are independently removably and movably mounted thereon in alinement, and constructed to permit any section to be swung up out of the way of a door-opening over which it is suspended, and retained in such upward position by the gravity of the superposed section placed to engage it.

This object we have accomplished by the means which are hereinafter described and claimed, and which are illustrated in the accompanying drawings, in which Figure 1 is an elevation of part of a silo which includes the vertical range of doors therein, showing sections of our ladder mounted over said doors in vertical alinement; Fig. 2 is a transverse vertical section of the parts shown in said Fig. 1, taken on the broken line 2—2 of said figure, looking in the direction indicated by the arrow, and Fig. 3 is a perspective view of one section of said ladder.

As shown the sections of our improved sectional ladder are mounted over the vertically ranged doorways of a silo, but may be positioned on any other part of the silo, or any other kind of building or structure, without departing from the principle of the invention, which is not dependent upon location of the sections, nor their respective forms, dimensions or materials.

Our ladder sections are particularly employed on silo structures, and supported over the door-openings thereof, for convenience. We have shown in said Fig. 1, therefore, only the pair of vertical side-beams or jambs 8 which inclose a plurality of vertically ranged door-openings closed by the usual solid doors 10. The jamb-timbers 8 are connected by means of cross-beams 9 to form said door-openings. The numeral 6 denotes several rods which surround the silo structure in a well-known way to support its

walls, and whose ends are adjustably connected by means of adjusting devices 7.

The ladder sections are alike in form and dimensions, and comprise for each a pair of spaced parallel vertical side-bars 1 rigidly connected at the bottom and near the top by means of the cross-bars 3 and 2 respectively. The bottom bar 3 has its opposite extremities bent in one direction for a purpose to be described.

The numeral 4 denotes a pair of clips or hooks, formed of a single piece of bar metal in each instance, suitably bent as shown to have a flat hook and a shank, the shank being transversely orificed, whereby it may be pivotally mounted upon the orificed upper end of the abutting side-bar 1 by means of a rivet or pivot-bolt 5.

Referring now to said Fig. 2, it will be seen that the hooks 4 are suspended upon the cross-rods 6, opening outwardly, the flat middle part of the hook in each case depending and lying adjacent to or contacting with a part of the underlying beam 9, the side-bars 1 being held suspended in spaced relation to the outer wall of the silo or over the door thereof which is immediately thereunder, with the ends of the bar-extremities or arms 3 engaging said door. When vertically alined in this way, the said sections serve as a sectional ladder. Being suspended over the doors 10, it often becomes necessary to have a doorway free from obstruction, when the door has been swung inwardly, and this is easily accomplished, by swinging up the ladder section immediately above the door-opening to be cleared, to permit the section which overhangs said opening to be itself swung upwardly under the first-mentioned section and over against the door above, the upper section when dropped then retaining the second section and preventing it from dropping back to its first position. A reversal of said process places the related sections in their first positions.

The sections are easy to suspend, operate or remove, are strong, simple and inexpensive.

Having described our invention, what we claim as new, and desire to secure by Letters Patent, is:

1. The combination with silo hoops or the

- like, of ladder sections positioned one above another, said sections being pivotally suspended at their upper ends on the adjacent silo hoops, each section being adapted to 5 swing upwardly and then be retained in its upward position by the overlying ladder section thereabove.
2. The combination with silo hoops or the like, of ladder sections positioned one above another, each section being composed of a frame and suspending-means pivoted thereto, said suspending-means being hung detachably on said silo-hoops, the frame-parts of the sections being adapted to swing upwardly to be received back of the section-frame immediately thereabove after the latter has first been swung upwardly to clear it, the frame above then holding the frame below in its raised position.
- 10 3. The combination with silo hoops or the like, of ladder sections positioned one above another, each section being composed of a frame and suspending-means pivoted thereto, said suspending-means being hung detachably on said silo-hoops, the frame-parts of the sections being adapted to swing upwardly to be received back of the section-frame immediately thereabove and held in 15 its raised position by the gravity and en-

gagement of the latter, each section-frame 30 having spacing-means mounted on its lower part to hold it spaced apart from the silo.

4. The combination with a structure having a plurality of vertically-arranged door-openings, of movable closures for said openings, supporting-means fixed above each door-opening, and ladder-sections arranged vertically above one another with a section 35 above each door-opening, each section being composed of side-bars fixedly connected by 40 means of cross-rungs of which one rung has parts projecting inwardly toward the door-closure thereunder to space the section therefrom, and hooks pivoted to the upper ends 45 of said side-bars and hung over said suspending-means removably and having shanks extending outwardly, said shanks spacing the upper parts of the sections from the silo, and permitting the sections to be swung upwardly, with the raised section retained 50 under the section above it by engagement therewith and the gravity of the latter, to clear the door-opening beneath the raised section.

Signed at Waterloo, Iowa, this 4th day of 55 April, 1918.

WILLIAM B. TROST,
FRANK KLEIN,
